MACHINE FOR USE IN THE MANUFACTURE
OF BOOTS AND SHOESBernhardt Jorgensen, Beverly, Mass., assignor to
United Shee Machinery Corporation, Paterson,
N. J., a corporation of New Jersey

Application September 22, 1932, Serial No. 634,317

25 Claims. (Cl. 12—7)

This invention relates to machines for manufacturing shoes or other footwear in which the lasted upper is secured to the sole by cement or other adhesive, the term "sole" being used herein generically to refer to what may be the insole. It is herein shown as embodied in a machine for carrying out the toe lasting step in the manufacture of gaiters and while this constitutes an important field of use, the invention 10 is not limited to use in the manufacture of this or of any particular class of footwear.

The machine of my invention includes a novel support upon which the sole and upper may be located in proper relation preparatory to lasting the upper by overwiping the margin of its toe end upon the sole and securing the overwiped margin permanently in such position by the application of adequate pressure. It will be understood that the margin of the upper and 20 the surface of the sole, or either of them, may be coated with an adhesive which acts, upon the application of pressure, to effect a permanent union between these parts of the shoe. As a convenient and effective means of maintaining 25 the sole in place on the support, a suction opening or openings may be provided in the support and the sole held by suction within the projecting margin of the upper while the latter may be accurately located and held in the proper 30 position with reference to the sole. In using the machine of my invention for toe lasting, a support may be employed having, as shown, an elongated or overhanging portion shaped to reach into the toe part of a shoe and adapted 35 to engage and hold the toe end of the sole and to fill out the corresponding toe end of the upper. In one aspect, therefore, my invention consists 40 in a machine provided with an elongated support having at its free end means for holding the toe end of the sole by suction thereon, arranged in cooperative relation with means for laying the margin of an upper inwardly over the sole while the sole is so held.

A further feature of the invention consists in 45 a support arranged for movement from an outer or work-receiving position, in which the operator may conveniently position the work thereon without obstruction or interference with other parts of the machine, to an inner or working position in close proximity to power-operated wipers or other means for laying the margin of the upper inwardly upon the sole, in combination 50 with means for rendering effective suction connections to the free end of the support when the latter is operatively positioned. As herein shown,

the suction connections are broken or interrupted when the support is moved to its work-receiving position and are reestablished by the movement of the support to its operative position. This construction leaves the operator free to position 60 the sole and upper upon the support in the first instance, with the assurance that the sole will be reliably held in such position without further attention on his part than may be required to present the work to the operation of the machine. 65

Preferably and as herein shown, upper clamping means are provided which are arranged to be brought into action when the support has been moved to its operative position. In order to position the support and the work 70 against the thrust of such upper clamping means and also against the thrust of the wipers, means are provided for positively latching the support in its operative position and incidentally in the position in which the suction connections are effective for holding the sole thereon. Such construction constitutes a further feature of the invention and contributes in adapting the machine for power operation with the development of 75 adequate pressure and speed. 80

The support herein shown is mounted not only for transverse movement in the manner explained but also for movement heightwise of the shoe in order to subject the overwiped margin of the upper and the sole to adequate pressure 85 to cause the adhesive to form a permanent union between the parts of the shoe. The desired results are effected by mounting the support or jack upon a vertically-movable carriage which is arranged to have its position controlled by suitable cam mechanism. The suction connections to the support are also contained to some extent in the jack carriage and the transverse movement of the support upon its carriage is utilized to interrupt and reestablish the effective connection 90 between an air pump and the suction opening or openings of the support. 95

These and other features of the invention will be best understood and appreciated from the following description of a preferred embodiment 100 thereof, selected for purposes of illustration and shown in the accompanying drawings, in which

Fig. 1 is a view of the machine in side elevation as seen from the left; 105

Fig. 2 is a view of the head of the machine, on an enlarged scale, in side elevation as seen from the right, a portion of the frame being broken away;

Fig. 3 is a plan view of the machine on a still 110

larger scale, a portion of the cover plate being broken away;

Fig. 4 is a view in longitudinal section on the line IV—IV of Fig. 3; and

5 Fig. 5 is a view in perspective of a shoe which has been operated upon by the illustrated machine.

My invention is herein illustrated as embodied in a machine which is in some respects of the 10 same general type as disclosed in my copending application Serial No. 629,514, filed August 19, 1932. For convenience, certain mechanisms which serve as well in one machine as in the other are identical in their construction and for a disclosure of details not fully shown herein reference may be had to said copending application. It will be understood, however, that the invention herein disclosed is in no sense limited to machines of this particular type but is applicable to 15 end lasting machines in general. It will be understood also that while the illustrated machine is adapted for toe end lasting, it could with slight modification in its work-supporting elements be adapted for heel-seat lasting.

25 The head frame 10 of the machine is supported at a convenient height by a suitable column and comprises a pair of vertically-disposed parallel side members connected at their upper ends by a transversely-disposed cover or top plate 11. 30 The top plate 11 is secured to the head frame 10 by suitable bolts and clamped between it and the top of the side members on each side of the frame is a guide bar 12, these cooperating to form guides for a horizontally-movable wiper slide 13.

35 A pair of swinging wiper carriers 14 is mounted beneath the forward end of the wiper slide 13 upon a downwardly-extending pivot pin 15 and wiper plates 16 are detachably secured to the forward edges of these carriers 14. The forward 40 and rear portions of each wiper carrier 14 lie on the same side of the axis of the pin 15 and the wiper plates 16 are, accordingly, closed when the rear ends of the wiper carriers are separated. The wiper plates 16 may be shaped in contour to 45 correspond to the particular footwear to be operated upon and are arranged to swing about the axis of the pivot pin 15, which coincides substantially with the center point in the margin of the toe. Each of the wiper carriers 14 is provided with an oblique cam slot 17, in which is received a cam roller 18 mounted upon a bolt 19 projecting downwardly through one of the guide bars 12. The axes of the rolls 18 are stationary and, consequently, when the wiper slide 13 is advanced, the rear ends of the wiper carriers 14 are 50 swung outwardly and the working stroke imparted to the wiper plates 16. As shown in Fig. 3, the wiper slide occupies its forward position and the wiper plates 16 have completed the operation of 55 overwiping or overlaying the margin of the upper, these plates being of such lengths as to act on the upper substantially as far rearwardly as the ball line of the shoe.

60 Reciprocation from front to rear is imparted to the wiper slide 13 by a cam lever 21 which, at its upper end, is received between ears projecting downwardly from the lower face of the wiper slide. The cam lever 21 is journaled to swing upon a transverse fulcrum shaft 22 extending 65 between the sides of the head frame 10. At its lower end it is provided with a cam roller 23 arranged to run upon the periphery of a disk cam 24 fast upon a cam shaft 25 mounted in bearings in the side members of the head frame 10. The 70 cam roller 23 is maintained in contact with the

periphery of the cam by a tension spring 26 secured to the lower arm of the cam lever 21 and to a transverse pin 27 which extends across the head frame between its two side members.

The work to be presented to the wipers above described may be supported on a gooseneck jack 33 which is pivotally mounted by a transverse pin 34 extending between the sides of a head 32 comprising a part of the jack carriage 31. The jack carriage is mounted for vertical movement in ways formed partly in the head frame 10 and partly in a vertical cover plate 30 bolted to the front thereof. The jack 33 is shaped so that it may enter and support the toe portion of a shoe and is provided at its free end with a toe plate 35 detachably secured thereto by an attaching screw 36. The contour of the toe plate corresponds to the outline of the insole to be employed and it will be apparent that toe plates of various shapes may be made available as the requirements demand.

The toe plate 35 herein shown is provided with suction openings by which the sole of the footwear may be temporarily secured in lasting position. To this end, the upper surface of the toe plate is provided with a marginal groove 37 with which communicate a series of transverse or radially-extending grooves 38, all of which lead to a centrally-disposed hole 39 extending through the body of the toe plate. A suction tube 40 is secured to the inner edge of the jack 33, passing upwardly through the free end thereof in alignment with the hole 39 in the toe plate, as shown in Fig. 4, and forming a substantially air-tight connection therewith. The tube 40 is curved to conform substantially with the inner edge of the jack 33 and is provided at its lower end with a reverse bend leading into the rear face of the jack behind its pivot pin 34. The lower end of the tube 40 communicates with a vertical bore 41 within the body of the jack which opens through its lower face in position to register with the upper end of an inclined air passage 42 extending downwardly and outwardly through the body of the head 32. A second suction tube 43 is connected to the lower end of the passage 42 and this extends rearwardly to an air pump 44 mounted at the rear of the head frame 10 and arranged to be continuously operated by means which will presently be described. The action of the pump 44 is to maintain suction throughout the system above described so that a vacuum will be immediately created in the grooves 37 and 38 of the toe plate whenever a sole is placed upon the toe plate. In this manner the sole is held firmly in the desired position and maintained in such position against displacement in the overwiping operation.

The jack 33 is pivotally mounted in the jack carriage to facilitate presentation of the work to the machine and to permit it to be swung from an outer or work-receiving position, indicated in dash lines in Fig. 2, to an inner or operative position, indicated in the same figure by full lines. A tension spring 45 extending between the rear end of the jack 33 and a portion of the head 32 of the jack carriage tends at all times to swing the jack forwardly into its operative position. In this position the lower end of the vertical air passage 41 is brought into substantially air-tight connection with the upper end of the inclined air passage 42 in the jack carriage and the suction of the air pump 44 is effective at the surface of the toe plate 35. When the jack 33 is swung outwardly against the

tension of the spring 45, the air connection is broken at this point and there is no effective suction at the surface of the toe plate.

In order to maintain the jack 33 against accidental displacement from its operative position, the lower branch thereof is provided with an abutment block 46 and with this cooperates a latch piece 47, notched at its upper end to receive the block 46, and pivotally connected at its lower end to the head 32. A tension spring 48 tends to swing the latch piece 47 always toward its engaging position. The latch piece may be conveniently disengaged by operating a curved sheet metal handle 49 which is secured to its upper end and which extends upwardly in general conformity to the shape of the jack 33. The handle 49 is thus located where it is naturally engaged by the hand of the operator in grasping the jack to move it out of operative position. In some cases, as suggested in Fig. 2, the handle 49 is disposed within the upper of the footwear upon the jack and it is adapted to be conveniently operated under such conditions by pressure transmitted through the upper.

The jack carriage 31, as already noted, is mounted for limited vertical movement. Its position is regulated and controlled by a bell crank lever 52 journaled upon a transverse shaft 53 extending between the sides of the head frame 10. The free end of the cam lever 52 is provided with a cam roller 54 arranged on the periphery of a disk cam 55 which is pinned to the cam shaft 25, already mentioned. A tension spring 56, extending between the lower arm of the lever 52 and the transverse pin 27, serves to maintain the cam roller 54 at all times in engagement with the periphery of the cam. The cam 55 is designed to elevate the jack carriage slightly, after the wipers have been advanced to the end of their operative stroke, for the purpose of subjecting the overwiped upper material and insole to pressure and to maintain such pressure for the desired period of the machine cycle. The cam 55 is shaped to release the jack carriage at the conclusion of the pressure-applying step, permitting its return to initial position.

A toe clamping band 60 is provided for conforming the upper material smoothly to the contour of the curved marginal face of the toe plate 35 and for maintaining it in such position during the overwiping operation. The toe band 60 is of flexible material and is yieldingly supported at its central point by a sliding bracket 61 which is mounted for free movement in ways formed in the upper surface of a forked slide 63, which will be referred to as the toe clamp slide. The toe band 60 is supported at each of its ends upon the free end of a link 62 and these links are pivotally supported at their rear ends on the toe clamp slide 63. The result is that when the slide 63 is advanced, the center of the toe band 60 is brought yieldingly into engagement with the center of the upper which is filled out at its toe end by the toe plate 35 and then, in the continued movement of the slide 63, the band is wrapped smoothly about the upper, automatically conforming it to the contour of the plate. The jack 33 is latched positively in position to withstand the thrust of the toe band during this operation by the action of the latch piece 47.

The toe clamp slide 63 is mounted to reciprocate in horizontal ways formed in guide plates 64 which are bolted in position beneath a U-shaped web 65, which comprises an integral part of the head frame and acts as a tie between the side

members thereof. The slide 63 is provided upon its lower face with a swivel head 66 which is connected through a substantially horizontal link 67 with the upper end of a lever arm 68 pinned to the shaft 22, which has already been described as serving as the journal for the wiper slide cam lever 21. At an intermediate point, the arm 68 is provided with a swivel head through which extends an operating rod 69. A compression spring 70, interposed between this head and a nut on the end of the rod 69, supplies a yielding connection between the two. At its forward and lower end the operating rod 69 is connected to the upper end of an arm 71 pinned to the inner end of a transverse shaft 72 which is journaled in a boss projecting outwardly from the left side member of the head frame 10. At the outer end of the shaft 72 is provided a forwardly-extending arm 73 which has a lost motion connection with the upper end of a treadle rod 75 connected at its lower end to a treadle 76. A tension spring 74 normally acts to elevate the arm 73 and the treadle and to rock the shaft 72 in a counter-clockwise direction. It will be seen that upon depressing the treadle 76 the shaft 72 will be rocked in a clockwise direction, as seen in Fig. 1, and through the connecting mechanism above described the toe clamp slide 63 will be yieldingly advanced and the clamping band 60 brought into operative position about the toe portion of the upper which is filled out by the toe plate 35.

The toe clamping band 60 is maintained in its operative position so long as the treadle 76 is held depressed. When the toe wipers 16 have made their working stroke and overwiped the margin of the upper about the toe, the upper is, of course, held securely in place upon the toe plate and there is no further necessity for maintaining the clamping band in its forward position. The treadle 76 must be fully depressed to trip the machine and the timing of the machine is such that the toe wipers engage the upper in their working stroke while the upper is still clamped by the toe band 60. The machine is brought to rest automatically with the toe wipers in their forward position, as shown in Fig. 3, whether or not the treadle is released. However, in order to restart the machine for the second portion of its cycle, the treadle must be released and the clamping band is, accordingly, retracted at that time to its initial position by the action of the spring 74, as shown in Fig. 1.

The main shaft 25 of the machine may be driven from any convenient source of power and, as herein shown, is provided upon its outer end with a roller or Horton clutch of which the driving member includes a sprocket wheel 85. The sprocket wheel is driven by a sprocket chain 84 from a reducing gear unit 82 mounted upon a bracket 83 extending rearwardly from the head frame 10. The reducing gear unit 82, in turn, is belt driven from a motor 80 supported upon a bracket 81 fast to the base of the column.

It is unnecessary here to describe fully the construction of the driving clutch since this is fully disclosed in my copending application above identified. It may be said, however, that associated with the driven member 86 is a roller cage having spaced projecting teeth 87 and 88 which are adapted to be engaged by a tripping dog 90 having a hooked end. The clutch is arranged automatically to engage when the tripping dog is moved to release one or the other of the teeth 87 or 88. The dog 90 is provided with a lifting pin 93 and with this cooperates a vertically-disposed

latch piece 92 pivotally mounted upon a rearward extension of the arm 73, above mentioned. A tension spring 91 extending upwardly from the forward end of the clutch dog 90 urges the latter always toward its operative position for disengaging the clutch but when the treadle 76 is depressed, the latch piece is lifted and a tooth formed thereon engages the lifting pin 93 so that the clutch dog is lifted and the clutch permitted to engage. The latch piece 92 is disengaged from the lifting pin 93 as soon as the machine is set in operation by one or the other of two pins 94 which project endwise from the driven member of the clutch 86, and thus a non-repeating action of the clutch is insured.

The machine herein described may be employed with advantage in the manufacture of various types of footwear and, in order to render the manner of its operation clear, this will be outlined in connection with footwear of the gaiter or overshoe type, such as that shown in Fig. 5 of the drawings. This shoe comprises a flexible sole 100 reduced in thickness about its margin, thus providing a feather which it is the practice to coat with an adhesive cement. The upper 101 herein shown is of rubberized fabric and similarly provided with a band of cement about its margin. In Fig. 5 the shoe is represented as having been operated on by the machine herein illustrated and in this process the margin 102 of the upper is overwiped about the toe portion of the sole and along the sides of the forepart and then subjected to pressure, so that the upper and sole are permanently united from the end of the toe substantially to the ball line of the shoe. The shank and heel-seat portions of the shoe are represented as having been lasted previously by the operation of the machine disclosed in my copending application.

The construction of the machine and the manner of its operation will be more clearly understood from a summary of the successive steps carried out in producing the shoe shown in Fig. 5. Assuming that the machine is stopped by the engagement of the clutch dog 90 with the tooth 87 and that the parts of the machine occupy their initial positions in the cycle, as shown in Fig. 1, the motor 80 may be assumed to be in motion and both the air pump 44 and the sprocket wheel 85 are being therefore operated. The operator may now grasp the jack 33, swinging the handle 49 to unlock the jack so that he may proceed to swing it outwardly into the dash line position shown in Fig. 2, whereupon in the toe plate 35 is conveniently exposed free and clear from all other parts of the machine and an opportunity afforded of conveniently placing the upper 101 in position with its margin conforming to the curved marginal face of the toe plate and projecting upwardly the proper distance beyond the plane of the sole supporting face of the plate. The toe end of the sole may also be accurately positioned upon the toe plate within the projecting margin of the upper. As already explained, the suction connection to the toe plate is interrupted while the jack is in its work-receiving position on account of the separation of the lower end of the air passage 41 from the upper end of the air passage 42. Having brought the sole and upper into the desired relation under the convenient conditions explained, the operator may now swing the jack 33 inwardly, bringing the toe part of the shoe into range of the path of the toe wipers 16 and of the toe band 60. In this operation, the jack

becomes locked in operative position by the action of the latch piece 47 and the suction connection to the toe plate is reestablished, whereupon the toe end of the sole is immediately held firmly by suction in place upon the upper surface of the plate. If the parts of the shoe are not properly positioned at this time, the operator may again unlock the jack and swing it outwardly for further adjustment, but if he is satisfied with the arrangement of the parts he may now proceed to depress the treadle 76.

When the treadle is depressed, the toe band 60 is first advanced through the connections above described and the margin of the upper is smoothly shaped and firmly clamped to the marginal face of the toe plate. In the continued depression of the treadle, the clutch is stripped and the shaft 25 set in rotation. The wiper slide 13 is thereupon advanced by the action of the cam 24 and the connections above described and the wiper plates 16 are moved forwardly and inwardly with respect to the shoe, engaging the upstanding margin of the upper and overwiping it upon the cemented feather surface of the sole 100. At substantially the conclusion of the advancing movement of the wipers, the cam 55 acts to elevate the jack and subject the sole and overwiped margin of the upper, which are now interposed between the toe plate 35 and the wiper plates 16, to a substantial compression, thus causing the adhesive to form a permanent union between these parts of the shoe. In the continued rotation of the shaft 25, the clutch tooth 88 is engaged by the clutch dog 90 and the machine brought to rest with the work under pressure.

In most cases the machine may be immediately restarted after the work has been subjected to a momentary pressure but, if desired, the restarting of the machine may be delayed for an appreciable interval. When the treadle is now depressed for the second time, the toe band is advanced in an idle movement and the clutch dog disengaged from the tooth 88. The shaft 25 is thereupon further rotated and almost immediately the cam 55 permits reverse movement of the cam lever 52 and lowering of the jack to initial position, thus releasing the pressure of the work against the wipers 16. When the pressure on the wipers has thus been released, the wiper slide 13 is moved rearwardly and the completed shoe may be removed from the machine after again releasing the jack 33 and swinging it outwardly.

The machine herein shown is equipped with wiper plates for overwiping the margin of the upper upon the sole and while this is a satisfactory and efficient manner of shaping the upper, other or different mechanism, depending on the nature of the footwear, may be employed, it being essential only that the margin of the upper be laid inwardly over the edge of the sole in position to be secured thereto.

While I have illustrated herein only footwear of the gaiter type, it will be understood that my invention may be advantageously embodied in machines for use in the manufacture of footwear of other types including shoes of various kinds in which adhesive material is employed in the shoe bottom as a temporary or permanent upper-securing medium.

Having thus described my invention, what I claim as new and desire to secure by Letters Patent is:

1. In a machine of the class described, a

- curved elongated support formed to extend within a shoe upper but of a contour mainly different from that of a shoe, said support having at its free end means for holding the toe end of a sole by suction thereon, and means for laying the margin of the upper inwardly over the sole while the sole is so held. 5 80
2. In a machine of the class described, an elongated support, a toe plate carried at the free end thereof and having means for holding the toe end of a sole by suction thereon, mechanism for clamping an upper against the sides of the toe plate to hold it in predetermined relation to the sole, and means for laying the margin of the clamped upper inwardly over the sole. 10 85
3. In a machine of the class described, an elongated support having a toe plate at its free end provided with a flat sole-supporting face bounded by a curved marginal face, said plate being provided with suction openings whereby the toe end of a sole may be held by suction thereon, means for clamping an upper in place against the marginal face of the toe plate, and means for laying the margin of the clamped upper inwardly over the sole while the sole and upper are so held. 15 90
4. In a machine of the class described, wipers arranged for movement in a predetermined path, an elongated support shaped at its free end to underlie the toe end of a sole and having a suction opening therein, said support being movable to present a sole and upper within range of said wipers and having suction connections which are rendered effective in such movement to hold the sole by suction thereon. 20 95
5. In a machine of the class described, wipers arranged for movement in a predetermined path, a support shaped to underlie the toe end of a sole and fill out a corresponding upper, said support having a suction opening therein and being movable with a sole and upper thereon toward the path of said wipers, means for clamping the upper in position upon the support after it has been so moved, and suction connections effective in such position of the support to hold the sole by suction thereon. 25 100
6. In a machine of the class described, power-operated wipers arranged for movement in a predetermined path, a support shaped to underlie the toe end of a sole and to fill out a corresponding upper, said support being arranged for movement to present a sole and upper to the action of the wipers, suction means operative during the wiping operation to hold the sole by suction on the support, and means for thereafter moving the support to compress the overwiped margin of the upper. 30 105
7. In a machine of the class described, a jack shaped to extend into the toe of a shoe and being provided at its free end with a toe plate having a flat sole-end supporting face with a suction opening therein and a curved marginal face of a contour to fill out the toe part of the upper, upper clamping means cooperating with the marginal face of the toe plate, and wipers operative to overwipe the margin of the upper upon a sole held by suction on the sole-end supporting face of the toe plate. 35 110
8. In a machine of the class described, a jack shaped to extend into the toe of a shoe and being provided at its free end with a toe plate having a horizontal sole-end supporting face and a curved vertically-disposed face of a contour to fill out the toe part of the upper, suction connections communicating with said sole-end 40 115
- supporting face whereby a sole may be held in place thereon, and means mechanically operated in sequence first to clamp the toe part of the upper to the vertically-disposed face of the toe plate and then to overwipe the margin thereof upon the sole while the latter is held in place by suction. 45 120
9. In a machine of the class described, a toe plate having a substantially flat sole supporting face bounded by a curved marginal face of a contour to fill out the toe part of an upper, the plate having a suction opening therein and an open peripheral groove located in its sole supporting face and communicating with said suction opening. 50 125
10. In a machine of the class described, end-lasting wipers, a jack for supporting a sole and upper in lasting relation arranged for movement from an inoperative position to present the sole and upper to the action of the wipers, and a suction system having an inlet in said jack whereby the sole may be held by suction thereon, said system being arranged to be rendered operative in the work presenting movement of the jack. 55 130
11. In a machine of the class described, end-lasting wipers, a pivotally-mounted jack for supporting a sole and upper in lasting relation and arranged to swing inwardly with the work to present it to the wipers, a suction opening in said jack, and suction connections arranged to be broken when the jack is moved to its outer position and to be reestablished when the jack is swung inwardly, whereby the sole may be held by suction during the operation of the wipers. 60 135
12. In a machine of the class described, power-operated wipers, a jack carriage, a jack pivotally mounted thereon and provided with a toe plate having a suction opening therein, and suction connections communicating with said opening and including registering passages in the jack and jack carriage respectively, arranged to be separated when the jack is swung in one direction and effectively connected when the jack is swung in the opposite direction. 65 140
13. In a machine of the class described, a pivotally-mounted jack shaped to enter a shoe and having a suction opening at its free end whereby a sole may be held thereon, suction connections adapted to communicate with said opening, means for locking the jack in position to render said connections effective, and releasing means therefor disposed adjacent to the jack. 70 145
14. In a machine of the class described, a jack carriage, a jack pivotally mounted thereon and having a suction opening at its free end, said jack and jack carriage having air passages adapted to register in one position of the jack, and yielding means tending at all times so to locate the jack. 75 150
15. In a machine of the class described, a jack carriage, a jack pivotally mounted thereon and having a suction opening at its free end, said jack and jack carriage having air passages adapted to register in one position of the jack, yielding means tending at all times to locate the jack in such position, and means for positively locking the jack in said position arranged to be released by the operator in grasping the jack preparatory to moving it out of said position. 80 155
16. In a machine of the class described, power-operated wipers, a jack shaped to enter a shoe and having a suction opening at its free end, said jack being mounted to swing transversely toward and from said wipers and also to move in a path normal to said wipers, and suction connections 85 160
- 90 165
- 95 170
- 100 175
- 105 180
- 110 185
- 115 190
- 120 195
- 125 200
- 130 205
- 135 210
- 140 215
- 145 220
- 150 225

to said opening effective in all positions of the jack in said normal path and arranged to be interrupted when the jack is swung away from the wipers.

3. 17. In a machine of the class described, power-operated wipers, a jack shaped to enter and fill out the toe end of a shoe and having a suction opening therein, said jack being movable transversely to position one end of a shoe beneath the wipers and also heightwise to press the overwiped material against the wipers, and air connections to said suction opening arranged to be broken when the jack is moved outwardly, reestablished when the jack is moved inwardly, and maintained while the jack is moved heightwise.

4. 18. In a machine of the class described, power-operated wipers, a curved jack having a suction toe plate at its free end and being pivotally mounted to swing to and from a position remote from the wipers, air connections communicating with said suction plate and extending at least in part through the jack, means for latching the jack in its inner position, and a releasing handle therefor extending within reach of the operator as he grasps the jack preparatory to swinging it toward said remote position.

5. 19. In a machine of the class described, power-operated wipers, a jack having a sole-retaining suction plate and being arranged to swing inwardly from work-receiving position to operative position beneath the path of the wipers, a toe band arranged to cooperate with the suction plate in clamping the marginal edges of an upper thereto, spring means for latching the jack against the pressure of the toe band, and cam-operated mechanism for advancing the latched jack toward the wipers to subject the overwiped material and sole to pressure against the wipers.

6. 20. In a machine of the class described, a frame having horizontally-movable wipers and a vertically-movable jack carriage mounted therein, cam mechanism for advancing the wipers and thereafter lifting the jack carriage, a goose-neck jack pivotally mounted upon said carriage and provided with a flat sole-retaining suction plate at its free end, yielding means tending at all times to swing the jack inwardly and locate its toe plate parallel to the path of the wipers, means for positively latching the jack in such position, an air pump, and connections between said pump and suction plate which are effective while the latter occupies its said position parallel to the path of the wipers.

7. 21. In a machine of the class described, movable wipers, a swinging jack having means for supporting and retaining thereon the toe end of a sole and for filling out an upper about the margin of the sole, a carrier for the jack, and auto-

matic mechanism for moving said carrier to force the jack toward the wipers when the latter occupy their overwiping position on the shoe bottom to press the overwiped upper against the sole.

8. 22. In a machine of the class described, movable wipers, a swinging jack having means for supporting and retaining thereon the toe end of a sole with an upper surrounding the same, a carrier upon which the jack is mounted, means for latching the jack in operative relation to the wipers, and power-operated means for moving the carrier with the jack so latched to force the jack toward the wipers to compress the overwiped margin of the upper against the wipers.

9. 23. In a machine of the class described, horizontally-movable wipers, a carrier movable in a vertical path beneath the wipers, a jack pivotally mounted on the carrier to swing to and from an operative position beneath the wipers and having thereon means for retaining the toe end of a sole in position to be surrounded by an upper, the wipers being arranged for operation when the jack is swung beneath them, and means for thereafter elevating said carrier by power to compress the overwiped upper and sole and form an adhesive union between them.

10. 24. In a machine of the class described, movable toe wipers, a carrier arranged for movement toward and from said wipers, a jack pivotally mounted upon the carrier to swing transversely to the path of the carrier and having a flat plate at its outer end for supporting the toe end of a sole and retaining the same in position thereon during the action of the wipers, means under the control of the operator for latching the jack against pivotal movement away from the wipers, and power-actuated mechanism for first operating the wipers to overwipe the margin of an upper upon the supported sole and then operating to move the carrier to compress such overwiped margin and sole between said flat plate and the wipers.

11. 25. A machine for lasting and fastening the toe portion of a shoe, comprising flat wiper plates mounted to sustain pressure exerted normally thereto, a curved elongated jack pivotally mounted to swing beneath the wiper plates and having at its free end a toe plate for supporting and retaining the toe end of a cemented sole, means for latching the jack in position to resist the advancing movement of the wipers in overwiping the cemented margin of an upper upon the sole supported on the toe plate, and means for bodily moving the jack while latched in such position to compress the overwiped and cemented faces of the upper and sole against the wiper plates and form an adhesive union between them.

BERNHARDT JORGENSEN.
